INVENTOR

Geo. L. Hall

UNITED STATES PATENT OFFICE.

GEORGE L. HALL, OF BROOKLYN, NEW YORK.

INSULATED RAIL-JOINT.

SPECIFICATION forming part of Letters Patent No. 712,131, dated October 28, 1902.

Application filed January 18, 1902. Serial No. 90,233. (No model.)

To all whom it may concern:

Be it known that I, GEORGE L. HALL, a citizen of the United States of America, residing in the borough of Brooklyn, city of New York, 5 county of Kings, and State of New York, have invented certain new and useful Improvements in Insulated Rail-Joints, of which the following is a specification, reference being had therein to the accompanying drawings.

10 My invention relates to joints between adjacent rails of a railway and to the insulation of one rail from the rail adjacent to it; and its objects are to provide means whereby the amount of insulating material used may 15 be decreased and what is used be put in such places as will be subjected to less wear and tear than has heretofore been accomplished.

To these ends my invention consists of a two-part fish-plate, means of uniting the two 20 parts of said fish-plate, and means of insulating the two rail ends and the two parts of the fish-plate from each other.

I hereinafter describe a rail-joint embodying the features of my improvements, and 25 then point out the novel features in the claims, having reference to the accompanying drawings, in which similar figures of reference indicate similar parts throughout the various views, of which—

30 Figure 1 is a plan view, partly in section, on lines 2 2 of Fig. 2 and 4 4 of Fig. 3. Fig. 2 is a side view. Fig. 3 is an end view, partly in section, on the line 3 3 of Fig. 1.

1 1 are ends of two railway-rails to be 35 joined and electrically insulated from each other.

2 and 3 are respectively parts of a fish-plate. Each of said parts 2 and 3 is provided with one or more lugs 4, offsetting from 40 the same, though in some cases they may be omitted. These lugs 4 may be so arranged as to be spiked to ties or so as to be run into the earth, or some of them may be arranged to be spiked to ties and others to be run into 45 the earth. Said parts 2 and 3 of said fish-plate are also provided with offsetting lugs 5, adapted to be united by one or more bolts, rivets, or other joining devices 6. 7 is insulating material, such as vegetable fiber, 50 adapted to be inserted between the rail ends and the two parts 2 and 3 of the fish-plates.

Of course it will be understood that said insulating material may be omitted from between the rail ends, provided air-space is left between said ends; but I prefer to insert the 55 insulating material as shown in the drawings. 8 is a thimble or bushing of insulating material adapted to prevent any electrical connection between the two parts of the fish-plate through the said bolts, rivets, or other 60 joining devices.

10 represents bolts or other devices to bind together the rail ends and fish-plates.

9 is a washer protecting the thimble or bushing 8. 55

What I claim, and desire to secure by Letters Patent, is—

1. An insulated rail-joint comprising two opposite two-part fish-plates, means of structurally uniting and electrically insulating the 70 two parts of each fish-plate, means of maintaining the rail ends from contact with each other, and a plurality of bolts passing through the two fish-plates and the rails.

2. An insulated rail-joint comprising two 75 opposite two-part fish-plates, each of the parts of said fish-plates being provided with an offsetting lug or lugs adapted to be spiked to a tie or otherwise held in place, means of structurally uniting and electrically insulating the 80 two parts of each fish-plate, means of maintaining the rail ends from contact with each other, and a plurality of bolts passing through the two fish-plates and the rails.

3. An insulated rail-joint comprising two 85 opposite two-part fish-plates, each of the parts of said fish-plates being provided with an offsetting lug or lugs adapted to be spiked to a tie or otherwise held in place, and an offsetting lug adapted to match with a similar lug 90 on the other part, a bolt or bolts passing through said last-named lugs, insulating material between said lugs and between the rail ends, insulating material between every of said bolts and one of said lugs, and a plurality 95 of bolts passing through the two fish-plates and the rails.

4. A fish-plate for rail-joints comprising two parts, each having a portion adapted to fit in the web of the rail, and an offsetting lug 100 adapted to match with a similar lug on the other part, a bolt or bolts passing through

said lugs, insulating material between said lugs and insulating material between every of said bolts and one of said lugs.

5. A fish-plate for rail-joints comprising two parts each having a portion adapted to fit in the web of the rail, an offsetting lug or lugs adapted to be spiked to a tie or otherwise held in place, an offsetting lug adapted to match with a similar lug on the other part, a bolt or 10 bolts passing through said last-named lugs,

insulating material between said lugs, and insulating material between every of said bolts and one of said lugs.

In witness whereof I hereunto affix my name, in presence of two witnesses, this 17th 15 day of January, 1902.

GEO. L. HALL.

Witnesses:

H. V. N. PHILIP,
J. F. BOUDREAU.
